UNITED STATES PATENT OFFICE.

JESSE B. HAWLEY, OF ST. CHARLES, ILLINOIS.

DESIGN FOR A SOUND-AMPLIFYING CABINET.

Application filed October 5, 1925. Serial No. 15,027. Term of patent 7 years.

To all whom it may concern:

Be it known that I, JESSE B. HAWLEY, a citizen of the United States, residing at St. Charles, in the county of Cook and State of Illinois, have invented a new, original, and ornamental Design for Sound-Amplifying Cabinets, of which the following is a specification, reference being had to the accompanying drawing, forming part thereof.

I claim:

The ornamental design for a sound amplifying cabinet substantially as shown.

JESSE B. HAWLEY.
